UNITED STATES PATENT OFFICE

2,185,852

DISCHARGE DEVICE

Martin Klopprogge, Berlin-Zehlendorf, Germany,
assignor to General Electric Company, a corporation of New York

Application June 5, 1939, Serial No. 277,497
In Germany April 19, 1938

4 Claims. (Cl. 250—27.5)

The present invention relates to vapor or gas-filled electric discharge devices of the grid-controlled type. While not limited thereto, the invention is particularly applicable to discharge tubes for use in generating "sawtooth" voltages such as are employed in television scanning systems.

It is a prerequisite of the use last referred to that the control constants of the tubes employed shall be highly uniform and invariable with time. It is one object of the present invention to provide tube structures which satisfactorily fulfill this requirement. Another object is to provide such tubes having a construction in which all the lead-in conductors may be brought in through a single stem press.

To this end, in accordance with the present invention the tube is constructed in such manner that the anode and cathode are arranged in side by side relation in substantial parallelism and both are embraced by the grid structure. The latter element is so formed in the region between the anode and cathode as to provide a restricted discharge passage of carefully regulated dimensions. The features which I desire to protect herein are pointed out with particularity in the appended claims. The invention itself, together with further objects and advantages thereof may best be understood by reference to the following description taken in connection with the drawing, in which Fig. 1 represents a side view partially broken away of a discharge device suitably embodying the invention; Fig. 2 is a sectional view taken on line 2—2 of Fig. 1; Fig. 3 is a side elevational view of an alternative embodiment of the invention; Fig. 4 is a cross-sectional view taken on line 4—4 of Fig. 3 and Fig. 5 is another cross-sectional view taken on line 5—5 of Fig. 3.

Referring particularly to Fig. 1 there is shown a glass envelope 10 which is assumed to enclose an ionizable medium such for example, as mercury vapor or argon gas or an appropriate combination of vapors and gases. Within the envelope there are arranged in side-by-side relation an indirectly heated cathode 11 of elongated configuration and a cooperating anode 12 which is substantially parallel with the cathode. As appears more clearly in Fig. 2 these electrodes are enclosed within a sheet metal grid structure 14 of generally tubular form. (By the word "tubular" in this connection, is meant any form having a substantially perimetricaly complete contour whether such contour be circular or non-circular.)

Construction of the grid structure is such that the anode and cathode are respectively enclosed within substantially separate chambers arranged in side-by-side relation and defined by the outer walls of the structure and by a wall portion 15 which extends transversely of the discharge path. The wall portion 15 is provided with a restricted opening 16 which may be carefully adjusted as to dimensions to produce the desired control characteristic of the device. The ends of the 10 grid structure are closed by means of transverse insulating members 18 and 19 which form in combination with the grid structure a substantially complete enclosure for the anode and cathode. One advantage of the arrangement specified lies in its effectiveness in completely shielding the discharge system from the effect of external influences. As a result of this feature, highly consistent operating results are obtained.

In order to support the structure so far described the envelope 10 is provided at its lower end with a reentrant stem press 21. This is equipped with a pair of support rods 22 and 23 which engage the insulating members 18 and 19. The cathode 11 is supported by being secured at its respective ends to the members 18 and 19. The anode 12 may either be similarly supported or may be, as shown, supported directly from the stem press 21. A plurality of lead-in conductors, numbered 25 to 29 inclusive, are sealed into the stem press and connected with the various electrodes. The construction described realizes the important advantage of providing a shielded discharge system which is supported and energized entirely from one end of the discharge envelope.

In Fig. 3 there is shown an alternative embodiment of the invention. In this figure parts corresponding to elements already described in connection with Fig. 1 are similarly numbered.

In this case the grid structure, numbered 31, comprises a perimetricaly complete metal member which is constricted at a central axial plane thereof, as indicated at 32, to provide a restricted passage between the cathode 11 and the anode 12. This structural modification represents a simplification and reduction in cost of the device.

Another feature of difference between the device of Fig. 3 and that of Fig. 1 lies in the manner of support of the electrode elements. In 50 the figure now under consideration the wall of the discharge envelope 10 is drawn in at the upper portion to provide a section 33 of reduced diameter. The supports 22' and 23" provided for the grid structure extend into this reduced 55

section and are supported by it through the agency of relatively flexible elements 36 and 37 which are of such size as to engage the wall of the envelope. This feature is best shown in Fig. 5.

In the arrangement of Fig. 3 the grid lead-in conductor is shown as being sealed at 38 through the upper part of the envelope. However, it may alternatively be introduced through the stem 10 press in the manner illustrated in Fig. 1.

While I have described my invention in connection with particular embodiments thereof it will be understood that numerous modifications may be made by those skilled in the art without departing from the invention. I, therefore, aim in the appended claims to cover all such equivalent variations as come within the true spirit and scope of the foregoing disclosure.

What I claim as new and desire to secure by 20 Letters Patent of the United States is:

1. An electric discharge device comprising an envelope containing an ionizable medium and provided with a reentrant stem press at one end thereof, an elongated anode and cathode arranged 25 in substantial parallelism within said envelope and extending in substantially the same direction as the said stem press, a grid structure forming a pair of elongated chambers which are positioned in side-by-side relation and which respectively enclose the anode and cathode, said chambers being in communication with one another only through a relatively narrow opening defined by a portion of said grid structure, and a plurality of lead-in conductors extending through 30 said stem press and respectively connecting with said anode, cathode and grid structure.

2. An electric discharge device comprising an envelope containing an ionizable medium, an elongated anode and cathode positioned in side-by-side relation within said envelope, a pair of plate-like insulating members extending transversely of the anode and cathode at the ends thereof, a sheet metal grid structure forming in combination with said insulating members a substantially complete enclosure for said anode and cathode, and means comprising a part of said 10 grid structure providing a restricted passage as the sole means of discharge between the anode and cathode.

3. An electric discharge device comprising an envelope containing an ionizable medium, an 15 elongated anode and cathode mounted in substantial parallelism within said envelope, a generally tubular and imperforate grid structure enclosing said anode and cathode, said grid structure being constricted along an axial plane there- 20 of to limit the discharge path between the anode and cathode to a relatively narrow opening.

4. An electric discharge device comprising a relatively elongated envelope, an anode and cathode mounted in side-by-side relation within the 25 envelope and having opposed surfaces which parallel the major axis of the envelope, and a grid structure forming a pair of chambers which are also in side-by-side relation and which respectively enclose the anode and cathode, said chambers being in communication with one another only through a relatively narrow opening defined by a portion of said grid structure. 30
